CONVEYER FOR HEAT TREATING
FURNACES

Clarence Winfred Spicer, Toledo, Ohio

Application August 5, 1931, Serial No. 555,167

3 Claims. (Cl. 198—193)

My invention relates to flexible metal belts especially that type which is used for the conveying of bodies to be heat treated through a furnace and has for its object to provide a structure which is light in weight with a maximum of strength. A further object is to provide a link of a design which will prolong the life of the belt.

In belts of this character heretofore used, the mass of metal in the belt was a great disadvantage because it required an immense amount of heat to heat the belt before the articles to be heat treated could be brought up to the required temperature and when attempts have been made to reduce the mass in the belt, weaknesses have developed causing failure in the belt. In my invention I provide a construction in which the maximum strength of the metal is utilized.

The foregoing and other features of my invention will now be described in connection with the accompanying drawings forming part of this specification in which I have represented my traveling belt in its preferred form after which I shall point out more particularly in the claims those features which I believe to be new and of my own invention.

In the drawings:—Figure 1 is a diagrammatic assembly in part section of my conveyer as embodied in a heat treating furnace.

Figure 2 is a plan view of a series of links in a belt of one of my preferred designs.

Figure 3 is a side view of same.

Figure 4 is a modification of link arrangement to present a belt that provides full area for small work.

Figure 5 is a modification of link presenting a smooth belt on both sides and therefore reversible to distribute wear.

Figure 6 is a side view of link shown in Figure 5.

Figure 7 shows a series of blanks which could be cut singly or in multiple from a strip before forming and welding with weld at end of link as shown in Figure 6.

Figure 8 shows a series of blanks as shown in Figure 7, the weld being in middle of the link as shown in Figure 5.

Figure 9 shows how belts now in use fail because of slight wear at the eyes.

Figure 10 shows a chain made of links constructed out of seamless or welded tubing.

Figure 11 is a side elevation of structure shown in Figure 10.

Figure 12 is an end view of construction similar to Figure 10 but with the ends of the tubes turned up to form guards at the edges of the belt.

Figure 13 is a side elevation of structure shown in Figure 12.

In carrying out my invention as illustrated in Figures 1 to 8, my endless belt comprises a plurality of links 10 and 11 made preferably from a suitable heat resisting metal ribbon, linked together upon a plurality of pintles 20. This belt passes over two drums or sprockets 30 and usually drags on a supporting table 40 positioned in a heat treating furnace 14. The links comprising my belt as illustrated in Figures 1 to 8 are made of sheet metal having heat-resistant characteristics and of substantially flat cross section formed at each end with eyes for engaging the pintles 20 formed by bending the material over on itself.

In the construction shown in Figures 2 and 3, the ends are bent so that they over-lap each other and are secured to the center of the link by riveting or by welding if desired as shown at 12. It will be observed that this link presents a flat side 13 which is substantially straight and this side is designed to drag on the table 40 whereby a maximum surface is exposed which gives longer life. End links may be formed, if desired, with a side flange which is bent up to form a rail as shown at 15.

In links illustrated in Figures 5, 6, 7, and 8 it will be observed that the ends of the blank do not over-lap but are butt welded after the preferred method of making welded tubing. In link shown in Figure 6 the weld is at 50. The blanks for this type of link are shown in Figure 7, while the link shown in Figure 5 the weld is at 60. Blanks for this modification are shown in Figure 8.

I may desire to form my links from seamless or welded tubing as shown in Figures 10, 11, 12, and 13. In that case the tubing may be the full width or any part of the belt and formed either oval or round and then flattened. The tubing 80 is provided with openings 81 which are cut out of the tubing either before forming and welding into tubing or can be cut out from the tube after welding. The tube is then flattened and assembled on pintles 20 as shown in Figure 11. Should it be desirable to have a guard 85 on the edge of the belt the ends of the tubing may be turned up as shown in Figures 12 and 13. This guard may serve both to retain the work on the top of the belt and as a guide co-acting with table 40 or other part of the device to keep the belt running in the desired position.

In belts of this character and with ordinary shape of link as shown in Figure 9, wear is rapid

because the eyes present at first only a line contact with the table which rapidly wears through as shown at 70 causing the belt to fail.

It will be obvious that a belt made of links after the design shown in Figures 1, 2, 3, and 4 uses less material than usual designs and presents a smooth belt surface on one side which gives a maximum of wear for non-reversible belts and that a belt made of links after any of the designs shown in Figures 5, 6, 10, 11 and 12 uses the least possible material for a belt having also the advantages of smooth surface on both sides and reversibility.

With my construction I not only provide a link with maximum surface contact with table but a belt that can be reversed thus greatly increasing the life of the belt.

It will be observed that with this construction the links are threaded on the pintles in a continuous line which provides a maximum of bearing surface.

I wish it distinctly understood that my flexible metal belt herein illustrated and described is in the form in which I desire to construct it but that changes or variations may be made as may be convenient or desirable without departing from the salient features of my invention and I therefore intend the following claims to cover such modifications as naturally fall within the lines of invention.

I claim:

1. In combination with a heat treating fur-

nace, a table; a conveyer to pass over said table comprising a series of links of heat resistant material of substantially flat cross-section; and eyes formed in the ends of said links by bending portions of the material into contact with one another to form a substantially flat surface arranged to expose a maximum wear area to said table, said portions of the material being secured by welding.

2. In combination with a heat treating furnace, a table; a conveyer to pass over said table comprising a series of links of heat resistant material of substantially flat cross section having portions thereof bent to form eyes at the ends of said links, contact between said portions being made at one of said eyes whereby substantially flat surfaces are formed on the faces of said links to expose a maximum wear area to said table, said flat surfaces being free from joints or connecting means.

3. In combination with a heat treating furnace, a table; a conveyer passing over said table comprising a series of links of heat resistant material of substantially flat cross section having portions thereof bent to form eyes at the ends of said links, the remaining portions forming substantially flat surfaces on the faces of said links to expose a maximum wear area to said table, said flat surfaces being free from joints or connecting means.

CLARENCE WINFRED SPICER.
